IGNITION SYSTEM

Edward M. Claytor and William J. Rady, Anderson, Ind., assignors to General Motors Corporation, Detroit, Mich., a corporation of Delaware

Application November 7, 1940, Serial No. 364,702

4 Claims. (CL 123—146.5)

This invention relates to ignition systems for internal combustion engines and more particularly to the type of system in which a current source such as a storage battery is used to supply the ignition current. In such system a periodic circuit make and break device called the ignition timer is used to connect the current source with an ignition coil having a primary in series with the timer and current source and having its secondary connected with an ignition distributor. In such system a manually operated switch is used for controlling the flow of current from the current source with the ignition apparatus. If the operator should fail to open this switch and if the engine should stop with the ignition timer contacts closed, the battery would discharge through the ignition coil and the coil might be overheated and damaged.

It is an object of the present invention to provide for automatically opening the ignition circuit in case the engine stops with the timer contacts closed and the operator fails to open the ignition switch.

Further objects and advantages of the present invention will be apparent from the following description, reference being had to the accompanying drawing wherein a preferred embodiment of the present invention is clearly shown.

In the drawing:

The drawing is a wiring diagram embodying the present invention.

Referring to the drawing, ignition apparatus comprises an ignition coil 10 having a primary coil 11 and a secondary winding 12 connected respectively with ignition timer 13 and distributor 14. The timer includes an engine operated cam 15 for engaging the rubbing block 16 of the circuit breaker lever 17 connected by a leaf spring 18 with a terminal 19 connected with the primary coil 11. The lever 17 carries a contact 20 for engaging a grounded contact 21. The ignition coil receives its current from a battery 22 connected with the coil through a manually operated switch 23 and through the contacts 24 and 25 of a relay switch 26 having a magnet coil 27. After switch 23 is closed, magnet coil 27 is energized by closing a push button switch 28 connecting switch 23 with coil 27. Coil 27 is connected with circuits 29 of a thermal switch 30 having a bimetallic blade 31 carrying a contact 32 normally engaging a grounded contact 33. The blade 31 is heated by a heater resistance 34 connected between coil 10 and contact 25 of relay 26.

To turn on the ignition, the operator closes the main ignition switch 23 (which may be locked

open by a key) and then closes the push button switch 28 whereupon relay magnet coil 27 will be connected with the battery and contacts 24 and 25 will be closed. The operator may then release the switch 28 as contacts 24 and 25 will remain closed so long as relay coil 27 is energized. Relay coil 27 will remain energized so long as contacts 32 and 33 of thermostat switch 30 remain closed. During the normal operations of the ignition apparatus the circuit through the heater resistance 34 as well as the primary coil 11 is closed only intermittently. Therefore, the heating effect of a heater resistance 34 is limited to such an amount that the thermal switch 30 will not open while the engine is running. If the engine should stop with timer contacts 20, 21 engaged and if the operator should fail to open switch 23, the continuous current flow through heater resistance 34 will be such to heat the bimetallic plate sufficiently to effect separation of contact 32 from contact 33. Then the relay coil 27 will be disconnected from the battery and contacts 24 and 25 will open and the circuit from the battery 22 to the ignition coil will be interrupted.

While the embodiment of the present invention as herein disclosed, constitutes a preferred form, it is to be understood that other forms might be adopted, all coming within the scope of the claims which follow.

What is claimed is as follows:

1. An ignition circuit comprising a current source, a timer, an ignition coil primary winding, a relay having a magnet coil and a pair of normally open contacts which, when closed, make a connection between the current source and the magnet coil and between the current source and the primary winding and timer, a thermal switch for normally making a connection between the current source and relay magnet coil, said thermal switch having provisions responsive to continuous current flow to the primary winding for causing the thermal switch to interrupt said connection made by it, but not responsive to intermittent current flow while the engine is running, a manually operated switch in parallel with the relay contacts and means independent of the thermal switch for rendering the relay magnet coil ineffective to hold the relay contacts closed.

2. An ignition circuit comprising a current source, a timer, an ignition coil primary winding, a manually operated switch for connecting the current source with the primary winding and timer, said switch having spring means biasing it to open position, a relay having a magnet coil

parallelling the primary winding and timer and a pair of normally open contacts parallelling said manually operated switch, a thermal switch for normally making a connection between the current source and the relay magnet coil, said thermal switch having provisions responsive to continuous current flow to the primary winding for causing the interruption of the connection made by the thermal switch, but not responsive to intermittent current flow while the engine is running, and a switch for disconnecting the current source from the relay magnet coil independently of the thermal switch.

3. An ignition circuit comprising a current source, a timer, an ignition coil primary winding, a manually operated switch for connecting the current source with the primary winding and timer, a relay having a magnet coil parallelling the primary winding and timer and a pair of normally open contacts parallelling the manually operated switch, and a thermal switch comprising a bimetal blade and a pair of normally closed contacts for making a connection between the current source and relay magnet coil, one of the contacts being actuated by the blade, and a blade heater in the circuit of the primary winding and timer so related to the blade that the blade will separate the contacts of the thermal switch in response to continuous current flow through the primary winding, but not in response to intermittent current flow while the engine is running.

and means independent of the thermal switch for rendering the relay magnet coil ineffective to hold the relay contacts closed.

4. An ignition circuit comprising a current source, a timer, an ignition coil primary winding, a manually operated switch for connecting the current source with the primary winding and timer, a relay having normally open contacts parallelling the manually operated switch and 10 having a magnet coil for effecting the closing of said normally open contacts in order that, when the magnet coil is energized, a connection between the current source and primary winding and timer will be made independently of the 15 manually operated switch, and a series circuit including the current source, said manually operated switch, said relay magnet coil, a second manually operated switch and a thermal switch, said thermal switch having provisions responsive to 20 continuous current flow to the primary winding for causing the interruption of the connection normally made by the thermal switch, but not responsive to intermittent current flow while the engine is running, said second manually 25 operated switch being operable to open the said series circuit whereby the relay magnet coil is rendered ineffective, independently of the thermal switch, to hold the relay contacts closed.
